MAX HERMSDORF, OF ESSEN-ON-THE-RUHR, GERMANY, ASSIGNOR TO
FRIED. KRUPP AKTIENGESELLSCHAFT, OF ESSEN-ON-THE-RUHR,
GERMANY.

LEVER-ACTUATED WEDGE BREECH-BLOCK.

No. 809,801.

Specification of Letters Patent.

Patented Jan. 9, 1906.

Application filed March 31, 1905. Serial No. 253,082.

To all whom it may concern:

Be it known that I, MAX HERMSDORF, a subject of the German Emperor, and a resident of Essen-on-the-Ruhr, Germany, have invented 5 certain new and useful Improvements in Lever-Actuated Wedge Breech-Blocks, of which the following is a specification.

The present invention relates to lever-actuated wedge breech-blocks in which the operating-lever engages a curved groove in the breech-block.

The object of the invention is to relieve the fulcrum-pin from the effect of firing by a simple, easy, and cheap construction.

15 One embodiment of the invention is shown in the accompanying drawings, in which—

Figure 1 is a side view of a part of the gun-breech, the breech-block being closed. Fig. 2 is a top view of the same with the upper wall 20 of the breech-opening broken away. Fig. 3 is a view corresponding to Fig. 2 with the breech-block partly open. Fig. 4 is a rear view of Fig. 1, partly in section on line 4-4, Fig. 1; and Fig. 5 is a bottom view of the upper wall of the breech-opening.

By means of an operating-lever CC', the fulcrum-pin D of which is journalized in the breech A of the gun-barrel, the breech-block B can be forced into the tapering breech-opening and locked therein. To attain this purpose, the arm C' of the operating-lever engages a cam-groove b' b² in the breech-block through the medium of a heart-shaped stud c². The part b' of the groove is inclined to the direction of movement of the breech-block, while the part b² of the groove is curved in an arc concentric to the axis of the fulcrum-pin B.

40 The arrangement thus far described is old. In order to relieve the fulcrum-pin D of the effect of firing the gun, I provide the following means: On the side opposite to the stud c² the lever-arm C' is provided with a boss c³. The side faces c⁴ and c⁵ of boss c³, which extend transverse of the longitudinal axis of the arm C', are concentric to the axis of the fulcrum-pin D. The boss c³ engages a groove a' (see also Fig. 5) in the upper wall of the breech-opening. The groove a' is curved in 45 an arc concentric to the axis of the fulcrum-pin D. The width of the groove a' corresponds to the width of the boss c³ in a direction radial to the fulcrum-pin. When the

breech-block is closed, (see Fig. 2,) the stud c² of the operating-lever is located in that part 55 b² of the groove that is concentric to the turning axis of the lever. In that position the arm C' of the operating-lever has passed the dead-center position relatively to the direction of opening movement of the breech-block, so that an unintentional opening of the breech-block cannot take place. A pressure exerted on the breech-block when the gun is fired and tending to open the breech-block will be transmitted directly to the breech by 60 means of the stud c² of the operating-lever and the face c⁴ of the boss c³, which abuts against the wall a² of the groove a', and the fulcrum-pin D is therefore relieved of the pressure caused by firing the gun. 70

Having thus described the invention, the following is what is claimed as new therein:

1. In a gun, the combination with the breech, the breech-block, and the operating-lever journaled in one of said parts and engaging the other part by its free end, of a boss on said free end of the operating-lever, the part in which the lever is journaled being provided with a curved groove in which said boss engages, whereby the shock caused by firing the gun is transmitted directly to the breech and removed from the fulcrum of the operating-lever.

2. In a gun, the combination with the breech, and the breech-block, of the operating-lever 85 journaled in one of said parts and having connection with the breech-block to move it transversely of the bore of the gun, the said part having a groove concentric with the journal of the operating-lever, and means on the lever movable in the concentric groove.

3. In a gun, having a breech-block and an operating-lever journaled in the breech and engaging the breech-block by its free end; a boss on said free end of the operating-lever, 95 and a curved groove in the breech engaged by said boss whereby the shock caused by firing the gun is transmitted directly to the breech and removed from the fulcrum of the operating-lever.

4. In a gun having a fulcrumed crank-lever and a wedging breech-block, formed with a groove engaged by a stud on the free end of the crank-lever; a boss formed on the side of the free end of the crank-lever opposite the 105 stud, and a groove formed in the side wall of

the gun-breech, concentric with the crank-lever fulcrum, and engaged by the boss when the breech is closed, whereby the effect of firing is transmitted directly through the stud 5 and boss to the breech.

5. In a gun, the combination with the breech, the breech-block, the operating-lever journaled in the breech, and means on one side of the lever engaging the breech-bolt to transmit motion thereto, of means on the opposite

side of the lever engaging the breech to transmit to the breech the shock imparted to the lever and relieve the fulcrum thereof.

The foregoing specification signed at Düsseldorf this 18th day of March, 1905.

MAX HERMSDORF.
